UNITED STATES PATENT OFFICE.

JOE W. WIRT, OF CHICAGO, ILLINOIS.

CARD-INDEX HOLDER.

1,297,522.

Specification of Letters Patent. Patented Mar. 18, 1919.

Application filed September 17, 1917. Serial No. 191,835.

To all whom it may concern:

Be it known that I, JOE W. WIRT, a citizen of the United States of America, and a resident of Chicago, county of Cook, and 5 State of Illinois, have invented certain new and useful Improvements in Card-Index Holders, of which the following is a specification.

The main objects of this invention are to 10 provide an improved form of card index holder for use in filing card records; to provide an improved construction and arrangement of a rack having a series of pockets wherein the record cards are supported one 15 above the other with a portion of each card exposed; to provide an improved frame for mounting said rack in position for use; to provide an improved form of record card for use with a holder of this kind; and to 20 provide an improved device of this character which is simple and inexpensive in construction and which is suitable for general use with all kinds of card records.

An illustrative embodiment of this invention is shown in the accompanying drawings, in which—

Figure 1 is a perspective view of the improved card index holder showing various arrangements of the card records thereon.

30 Fig. 2 is an enlarged detail illustrating one form of construction of the rack for supporting the cards.

Fig. 3 is a similar view of a modified form of rack.

35 Fig. 4 is a back view of the construction shown in Fig. 3.

Fig. 5 is a perspective view of the improved form of record card for use in a device of this kind.

40 Fig. 6 is a transverse sectional elevation taken on the line 6—6 of Fig. 1, the rack being omitted.

This improved card index holder comprises a rack having partitions which consist 45 of a plurality of superposed strips or sheets of comparatively thin flexible material, such as cardboard, projecting successively one beyond the other. The rack is supported on a frame in such a manner that record cards 50 may be inserted in the pockets formed between adjacent partitions, so that a part of the record on each record card is exposed to view.

In a rack constructed in accordance with 55 the embodiment shown in Fig. 2, the partition cards 1 are supported in their super-

posed projecting relation by means of a block of base strips 2 which are secured together in corresponding superposed projecting relation by means of staples or metal 60 stitches 3. The exposed parts of the strips 2 are coated with a suitable adhesive, so that the lower edges of the respective partition cards 1 may be secured thereto. The thickness of the strips 2 is somewhat greater than 65 the thickness of the partition cards 1, so as to provide shoulders 4 on which the record cards 5 are supported when inserted between the partition cards 1.

In the embodiment shown in Fig. 3, the 70 partition cards 1 are superposed directly upon each other and are secured together by strips of tape 6, which are attached to the exposed parts of the cards 1 along the back thereof, as shown in Fig. 4. In this 75 construction, the record cards rest on the tape where it is exposed at the bottom edge of the partition cards.

In either of the modifications shown, the lateral edges of the partition cards 1 are 80 free, so that there may be a relative shifting of the upper portions of said partition cards as they are bowed out when the record cards 5 are inserted in the pockets.

The frame for supporting the rack 85 comprises a rectangular construction, including a back 7 having channel-shaped members 8 secured to the lateral edges thereof, whereby the flanges 9 of said channel-shaped members are spaced away from the plane of 90 the back 7 so as to provide grooves 10. The distance across the frame back 7 from the bottom of one groove to the bottom of the other is substantially the same as the length 95 of the partition cards 1, and the free edges of the partition cards 1 are loosely received in the grooves 10 under the flanges 9. The base of the rack seats in a groove 11 formed at the bottom of the frame (Fig. 6).

The frame is provided with means, herein 100 shown in the form of pins 13, by which it may be supported similar to a leaf in a book, either in a vertical position or in an inclined or nearly horizontal position, depending upon the kind of records to be filed.

With the rack assembled in the frame, the record cards 5 may be inserted in the pockets formed between the partition cards 1, and arranged in alphabetical, numerical, or some other order. The depth of the pockets corresponds with the record cards, so that the edges of the record cards are exposed one 110

above the other. Where the width of the rack is greater than the width of the record cards 5, the cards 5 may be placed in the pockets of the rack in staggered relation, as 5 shown in the upper part of Fig. 1, either with one card in a pocket or with two cards in a pocket, as circumstances may demand.

Where it is desired to have the lower edge of the record card exposed instead of the upper edge, a form of record card such as shown in Fig. 5 is made use of. This card comprises parts 14 and 15 hinged together by a tape 16, so that one of the parts may be inserted into the pocket between adjacent partition cards 1, and the other part resting on the holder as shown in the lower portion of Fig. 1.

Although but two specific embodiments of this invention have been herein shown and described, it will be understood that other modifications may be devised and numerous details of the modifications shown omitted or altered without departing from the spirit of this invention as described by 25 the following claims.

I claim:

1. A card index holder, comprising a rack formed of a plurality of partition cards superposed and projecting successively one beyond the other, means securing said cards together in said superposed projecting relation, and a frame having laterally disposed grooves at the sides thereof spaced apart substantially the length of said cards and adapted to receive the lateral edges thereof for the purpose of supporting said rack in position to permit record cards to be filed between said partition cards.

2. A card index holder comprising a rack 40 formed of a plurality of partition cards superposed and projecting successively one beyond the other, means securing said cards together in said superposed projecting relation and leaving the lateral edges free, and 45 a frame having laterally disposed grooves at the sides thereof spaced apart substantially the length of said cards and adapted to receive the free edges thereof for the purpose of supporting said rack in position to 50 permit record cards to be filed between said partition cards.

3. A card index holder comprising a rack 55 formed of a plurality of partition cards superposed and projecting successively one beyond the other, means securing said cards together in said superposed projecting relation and leaving the lateral edges free, and a frame having a back provided with flanges along the lateral edges thereof spaced away 60 from the plane of the back so as to provide grooves adapted to receive the free ends of said sheets for the purpose of supporting

said back in position to permit record cards to be filed between said partition cards.

4. In a card index holder, the combination 65 of a rack comprising a plurality of superposed strips projecting successively one beyond the other, means securing said strips in said superposed projecting relation, a plurality of partition cards secured along their 70 respective edges to the exposed portions of said strips, and means for supporting said rack in position to permit record cards to be filed between said partition cards.

5. In a card index holder, the combination 75 of a rack comprising a plurality of superposed strips projecting successively one beyond the other, means securing said strips in said superposed projecting relation, a plurality of partition cards of less thickness than 80 said strips secured along their respective edges to the exposed portions of said strips, and means for supporting said rack in position to permit record cards to be filed between said partition cards and rest on the 85 respective strips.

6. In a card index holder, the combination 90 of a rack, comprising a plurality of superposed strips projecting successively one beyond the other, means securing said strips in said superposed projecting relation, a plurality of partition cards secured along their respective edges to the exposed portions 95 of said strips, with the ends thereof projecting beyond the ends of said strips, and a frame having laterally disposed grooves at the sides thereof spaced apart substantially the length of said partition cards and adapted to receive the free ends thereof for the purpose of supporting said rack in position 100 to permit record cards to be filed between said partition cards.

7. In a card index holder, the combination 105 of a rack comprising a plurality of superposed strips projecting successively one beyond the other, stitching securing said strips in said superposed projecting relation, a plurality of partition cards cemented along 110 their respective edges to the exposed portions of said strips, and means for supporting said rack in position to permit record cards to be filed between said partition cards.

8. A card index holder, comprising a plurality of partition cards superposed and projecting successively one beyond the other, 115 and a record card for use with said holder having overlapped parts hingedly connected together, one of said parts being adapted to be inserted between adjacent partition cards so as to support the other part exposed on 120 said holder.

Signed at Chicago this 15th day of September 1917.

JOE W. WIRT.
